UNITED STATES PATENT OFFICE.

AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

SEWING MACHINE.

1,420,580.

Specification of Letters Patent. Patented June 20, 1922.

Application filed August 28, 1917. Serial No. 188,544.

To all whom it may concern:

Be it known that I, AUGUST R. SCHOENKY, a citizen of the United States, residing at Somerville, in the county of Middlesex and 5 State of Massachusetts, have invented certain new and useful Improvements in Sewing Machines, of which the following is a specification, reference being had therein to the accompanying drawing.

10 This invention relates to sewing machines; and more especially to sewing machines wherein a barbed needle is arranged so as normally to advance through the work to receive a thread loop and to retract to draw such loop through the work, and a looper is arranged to form a thread loop on the barb of the advanced needle, and a take-up for drawing tight the successive 15 stitches, there being a stitching shaft and 20 timed connections from the shaft for actuating the needle, the looper and the take-up in harmony through cycle after cycle during the normal stitching operations.

An example of such machines is one 25 wherein the barbed needle is curved and cooperates with the other sewing instruments to form chain stitches, for example in the well known welt and turn shoe sewing machine.

30 The objects of this invention are generally to improve the operation and convenience of sewing machines of the kind above referred to, and more especially to provide an improved means whereby when the machine is 35 stopped the shoe or other work may be readily extracted without hindrance from the needle or thread. Heretofore this object has been attempted by forming the objectionable loop on the needle barb when 40 stopping the machine and then in some way reversing or operating the machine or certain of its parts to remove the loop or free it from the needle; but all such devices have required either a reversing stop motion, 45 which is highly objectionable, or complication and weakening of mechanism.

To make the present invention clear I will first explain the cycle of stitching movements. Each stitch may be said to be completed when it has been drawn tight by the take-up. At this moment the needle is extending through the work to or nearly to its advanced position; the looper now moves so as to place a loop on the needle barb. 55 This is followed by the retraction of the

needle, which draws the loop through the work, while at the same time the take-up gives thread. After the complete needle retraction it next advances through the loop just formed, penetrating the work at a new 60 point, and as the needle advance continues the take-up operates to draw tight the thread and loop, which usually is accomplished by the time the needle again reaches its advanced position. This completes the 65 cycle. Whenever the machine is stopped, unless this cycle of movements is completed, the final stitch remains incomplete and loose. If the shaft be stopped when the needle is advanced, it is impossible to remove the 70 work because engaged by the needle. If the shaft is advanced somewhat further so as to retract the needle through the work, this draws another or extra thread loop through the work which again cannot be extracted 75 from the machine because held by such extra loop and needle barb.

With the present invention I obviate all these difficulties by a means of any suitable 80 nature forming part of or associated with the needle actuating connections for rendering abnormal or inoperative the needle stroke or timing when stopping the machine, whereby during the forward movement of the stitching shaft the needle will 85 not come to its loop receiving position although the looper perform its normal loop forming movement as usual. I preferably accomplish this by means of an abnormal needle stroke, for example by making provision to reduce the extent of advance of the needle so that although it will properly co-act with the take-up it will not move to the usual advanced point where in the regular 90 cycle it receives a loop from the looper. The means for giving this result being associated with the needle actuating connections permit the various motions and rotations otherwise to proceed as usual, and the shaft being finally stopped at the proper point the work and needle are disengaged and there is no objectionable extra loop to prevent the convenient extraction of the work.

I do not claim to be the first to secure 105 these broad results by control of needle movement in the final cycle, the present improved mechanism being subordinate to the pending application of F. E. Valois, filed July 31, 1916, Serial No. 112,230.

The invention might be embodied in numberless mechanical forms but merely by way of illustration I present the accompanying seven sheets of drawings showing a welt and turn shoe sewing machine embodying one form of the invention.

Figure 1 is a left elevation of a complete machine of this type, and the parts are supposed to be shown in their position at the 10 end of a stitch cycle when running in a normal manner at full speed.

Figure 2 is a partial left elevation of the head of the machine, taken partly in section on the plane 2—2 of Fig. 4.

15 Figure 3 shows the final stopped position of the control disk or cam shown in Fig. 2.

Figure 4 is a plan view of the parts shown in Fig. 2.

20 Figure 5 is a front elevation, partly in central section, of the mechanism adjacent the left end of the stitching shaft.

Figure 6 is a left elevation, partly in section, on the plane 6—6 of Fig. 4, showing the mechanism to the right of said plane and 25 for convenience also the members 57 and 58, which in reality are to the left of said plane. Fig. 6, like Figs. 1, 2, 4 and 5, shows the parts in their position at the end of the stitch cycle with the needle advanced, the 30 parts being also shown in dotted lines with the needle fully retracted.

Figure 7 is a view similar to Fig. 6 showing the position of the parts at the end of a stitch cycle when the present invention 35 has come into play to bring about an abnormal short needle stroke and prevent the formation of the objectionable extra loop.

Figure 8 is a detached plan view of certain parts shown also in Figs. 4 and 6.

40 Figure 9 is a section of the same parts taken on the plane 9—9 of Fig. 6.

Fig. 10 is a left elevation, and Fig. 11 a plan view, showing that part of the mechanism which has to do with the actuation of 45 the take-up.

Fig. 12 is a left elevation, and Fig. 13 a plan view, showing that part of the mechanism which has to do with the actuation of the looper.

50 The shoe X is shown in its proper or inverted position in which it is supposed to be guided by hand as the stitching progresses. The upper x of the shoe, the welt or strip x', and the insole x² or rather the lip x³ thereof, 55 may be mutually united by the stitching in this type of machine. Above the base 11 of the machine is a tall post 12 carrying the head or stitching mechanism 13 at the top. The actuating or stitching shaft 21 may be

60 power driven by the belt 14 engaging on power pulley 15 which through bevel gears 16 rotates a grooved pulley 17 from which the belt 18 extends upwardly toward the head of the machine and engages a grooved 65 extension 19 of the hand wheel 20 which is

keyed to the left end of the stitching shaft 21.

The connections by which the stitching shaft drives the needle 22, the looper 23 and the other stitching instruments, are shown 70 as of the crank, link and lever type substantially as illustrated in Patents Numbers 1,288,366 of December 17, 1918, and 1,361,952 of December 14, 1920, which may be referred to for illustration and description of many 75 details and other matters unnecessary to particularize for purposes of the present invention. Some of the operative instruments employed in the welt and turn machine are the work support 24, the channel guide 25, 80 the thread hook 26, the take-up 27, the feed point 28, and the welt guide and feed member 29, all of which may be substantially as shown in said patents. As the stitching shaft normally advances during the stitching, it actuates or controls the various instruments in harmony in a manner generally well known or made clear in said patents. For example, the looper 23 which is hollow 90 for the passage of the thread y, is rotatable about its own longitudinal axis 30 for somewhat over one rotation and then return so that the nose or extremity of the looper in its normal movement passes or forms a loop around the barb of the advanced needle 22, as will be clear from Fig. 6. The details of the looper connections do not concern the present invention which indeed enables the heretofore known type of looper and connections to be employed without change in 95 form or operation. The train of actuating elements includes bevel gears 30^a between the looper and the short shaft 30^b which carries a pinion 30^c oscillated by a swinging rack 30^d, which takes its motion from link 100 and lever connections from the crank shaft 21, as shown in Figs. 12 and 13 and more fully explained in said patents. Also the take-up 27 may be of the well known type 105 swinging about an axis 41 so as to yield and take-up the thread at the proper points in the cycle. The connections are sufficiently shown in Figs. 10 and 11 and explained in 110 said patents.

Coming to the needle mountings and connections which more particularly concern us, the needle is shown rigidly secured upon a carrier or block 35 fitted to oscillate about an axis or pivot 36 so that in the advance stroke the curved needle swings concentrically through the insole lip, the upper and the welt, to its loop receiving position adjacent the looper 23.

The connections from the stitching shaft 21 to the needle block and needle may comprise the following mechanical members. Formed upon the shaft 21 is a crank 38. A pitman or link 39 extends from this crank to the extremity of a swinging arm 40 fulcrumed at 41. From the pivot or stud 42, 125

which connects the link and arm, extends a link 43. At the lower extremity of this link is a stud 44 which connects the link and the two parts 45 and 46 of a needle lever which is fulcrumed on a stud or shaft 47. The lever 45, 46, is normally rigid throughout its length during stitching, and its forward or free end is connected by a curved link 48 with the needle block 35.

10 In Fig. 6 the reference numbers are applied only to the parts shown in full lines indicating the extreme advanced position of the needle. The extreme retracted position is clearly indicated by the dotted lines in 15 the same figure. Normal operation of these parts during stitching is that as the crank 38 travels around and around, the link 39 causes the arm 40 to swing up and down and thence through the link 43 swings the needle 20 lever up and down, this motion being communicated by the link 48 to the needle block and needle, all in harmony with the movements of the looper, take-up and other instruments.

25 In order to render the needle stroke inoperative at suitable times so that the needle will not come to its loop receiving position, I introduce into or associate with the needle actuating connections a suitable contrivance 30 which might be applied at any point in the train of connections 21, 38, 39, 40, 41, 42, 43, 44, 45, 46, 47, 48, 35 or 36. As an illustrative embodiment which is of practical utility, simplicity and convenience, I have 35 taken the needle lever 45, 46 and constructed it of two portions so as to permit at the proper time a relative movement which can render abnormal the needle stroke and which can be so controlled that when the machine 40 is stopped, the needle, during the advance of the stitching shaft, will fail to move forward to its loop receiving position.

The stud 44, which connects the two lever parts 45 and 46, permits the outer lever part 46 to move relatively so as to produce the desired effect which is transmitted through the subsequent connections 48, 35, 36, to the needle. In the normal operation this action is prevented by reason of a rigid extension 50 49 from the lever part 46 to the fulcrum shaft 47. It is obvious that so long as the extension 49 is held in rigid relation to the fulcrum 47 or the arm 45 there will be no abnormal movement, but that if the extension 55 49 be relatively swung about the pivot 44 this will swing the lever part 46 and change the throw of the needle. The extension 49 where it engages the fulcrum 47 is formed with a slotted head 50 so that it 60 may swing from its normal position indicated in Fig. 6 to an abnormal position indicated in Fig. 7.

Obviously, the effect of swinging the extension 49 downwardly from the Fig. 6 to 65 the Fig. 7 position during the advance of the

needle, will be to swing upwardly the lever part 46 and the link 48 thereby relatively retarding the needle. Thus, as shown in Fig. 7, the needle instead of advancing completely to its loop receiving position which is indicated in dotted lines, is caused to advance only to a position short of that so that it will avoid taking the loop notwithstanding the looper performs its normal movements.

75 The manner in which this action is performed, whether by hand or foot control, or whether timed by a cam or its equivalent, or operated by or simultaneously with a stop motion, may be variously modified. I have 80 shown a downward link 51 from the extension 49 and from this a link 52 connected to a fixed stud 53, so that by means of a third link 54 the links 51 and 52 may be brought to their Fig. 6 position which locks 85 the extension 49 as shown, or may be brought to the Fig. 7 position, during which adjustment the extension 49 is swung down, as shown, thus relatively lifting the forward end of the needle lever and retarding 90 the advance of the needle, as explained. The link 54 may be actuated by an arm 55 extending downwardly from a rock shaft 56 which at a convenient point in its length is provided with an arm 57 by which it may 95 be swung, this arm being shown as provided with a cam roller 58 so that the described abnormal needle movements may if desired be cam effected in proper timing.

100 The mechanical structure and arrangement of the members 47, 50, and 51, is shown in plan view in Fig. 4, and the details are shown in Figs. 8 and 9 where it is indicated that the upper end of the link 51 is engaged by a tongue and groove device 59 with the head 50 of the extension 49 so that the link may maintain its engagement with the head for raising and lowering it, as explained, without interference from the swinging of the head.

110 For convenience I have shown a pedal operated control for the described needle stroke modifying action as will be fully explained. The driving power may be uncoupled by shifting either the belt 14 from pulley 15 or belt 18 from pulley groove 19, and it is convenient to arrange that the same pedal action which controls the needle stroke modifying mechanism will also effect the shifting of the belt to throw off power, and preferably will also apply some kind of stopping device to bring the shaft finally to rest in a definite position with the needle disengaged from the work and, as a consequence of the present invention, with the 115 needle barb free of the thread. For this purpose various types of stop motion may be employed, such for example as that described in my Patent No. 1,085,093 of January 20, 1914, wherein the shaft passes 120 125

through progressively decreasing driving speeds to the stopping point; or that described in Patent No. 818,159 of April 17, 1906, wherein the driving speed is first stepped down to a fixed slow speed which is then thrown out and stoppage caused by impact.

I will describe an arrangement wherein when the machine pedal is released a control cam and a stop motion are thrown into action, the cam acting during the final advance of the shaft to apply the mechanism of my invention so as to render the needle stroke abnormal and prevent its coming to its loop receiving position.

The pedal 60 which is held depressed during stitching has a tendency to rise due to the spring 61. A rod 62 is lifted when the pedal is let up and this acts by a reversing lever 63 to pull downwardly the rod 64 which, as seen in Fig. 5, extends to the horizontal arm of a bell crank 65, the other arm of which shifts a slide rod 66 carrying a belt shifter 67, which throws the belt 18 from its operative pulley groove 19. In this way the power is disengaged. From the top of rod 64 extends a link 69 to a second bell crank 70, the upward arm of which carries a stud engaging a grooved collar 71 formed upon the right hand side of a disk 72 keyed to the shaft 21. This disk at its right face is formed with a cam groove 73 normally inoperative, but adapted to engage with the cam stud 58 previously mentioned. When the machine is running the disk 72 is held to the left, as seen in Fig. 5. When the disk is moved to the right in stopping the machine it will engage with the stud 58, as seen in Fig. 2. After such engagement the eccentric portion of the cam 73 throws the stud 58 upward and thereby, as explained on Fig. 6, swings the links 51 and 52, depresses the extension 49, and retards the needle in its final advancing movement. Fig. 3 which shows the shaft finally stopped by impact, indicates that the stud 58 has performed its function and has returned to its normal position thus restoring the parts in readiness for further stitching and with the needle disengaged from the work to permit the latter to be removed and replaced.

The disk 72 is guarded against shifting to the right at the wrong time not only by the stud 58, as explained, but by a pin 74 which normally stands to the right of the disk, as seen in Fig. 5, and is yieldable downwardly against the resistance of a spring 75. The disk, as more clearly shown in Figs. 2 and 3, is provided with a peripheral recess 76 and a stop shoulder 77, all properly arranged to secure the correct order of events. The disk can only shift to the right as its recess 76 comes opposite to the pin 74, and thereafter the shaft makes between a

half and a whole revolution prior to the impact of the shoulder 77 against the pin 74 which thus gives final stoppage in a position with the needle out of the work.

In order to reduce the shock of impact a brake may be applied between the throw off of power and the impact and this braking action may involve a slow forward drive so as to preclude premature stoppage. When the belt 18 is shifted from the pulley groove 19 it passes to the groove 79 formed on an annular member 80 freely rotatable about the stitching shaft. This member 80 carries planet pinions 81 having sufficient axial length to engage two other pinions, namely the pinion 82 keyed to the stitching shaft 21, and the pinion 83 formed on a sleeve 84 which is loose upon the shaft 21 but adapted to be prevented from rotation by a friction band 85 hung from the bracket 86 mounted on the shaft bearing 87. The pinions 82 and 83 are of different number of teeth so that when the member 80 is rotated by the belt 18 it can impart a slow differential movement to the shaft. The brake band 85 is applied to hold the sleeve stationary by means of a device 88 which is connected to rise and fall with the stop pin 74 so that when the stop pin is thrown down by the disk the brake is applied for about three-fourths a rotation and then released.

The action of such a stop motion is that after the pedal is released the disk 72 tends to move toward the right and does so as the pin 74 comes opposite the disk recess 76, while at the same time the belt is shifted from the pulley groove 19 to the groove 79 of the annular member 80. Immediately the pin 74 is cammed down as it passes out of the recess 76 and this pulls down on the device 88 which thereby applies friction to the sleeve member 84. This member through the gears 81, 82, 83, tends to impart slow drive to the shaft, and the employment of friction in bringing the sleeve to rest insures an easy and shockless retarding. The slow speed drive continues until finally the pin 74 is impacted by the shoulder or projection 77 of the disk which gives final stoppage with practically no shock, and the slight elevation of the pin 74 disengages the friction device 88 thus releasing the slow speed drive. In the meanwhile, as the final stitch cycle was completed the needle was prevented from advancing to loop receiving position and therefore, subsequently, when the shaft is stopped with the needle out of the work it is also free of thread. The abnormal or shortened advance stroke of the needle which prevents its taking the loop, is followed by a correspondingly shortened reTRACTING stroke, as explained, so that at the final stop the parts are again all in normal 130

relation. For restarting it is merely necessary to depress the pedal, and as the cam 73 is thus caused to disengage the roll 58 no further abnormal action takes place but 5 the two parts 45 and 46 of the needle lever retain their rigid and substantially unitary character. The belt moving to the pulley 19 causes full speed drive, and stitching proceeds.

10 A contrivance may be used for normally holding the links 51, 52 in alignment, and thereby the two parts 45 and 46 of the needle lever in rigid relation during the stitching; and instead of a mere spring I 15 prefer a positive locking contrivance for this purpose. This may be applied, for example, to the arm 57. A locking arm 90, see Fig. 5, which is provided with a locking pin 91, is adapted to be swung so that 20 the pin will enter the socket or hole 92 in the arm 57, and when this occurs the arm, and consequently the links 51, 52, are held against movement from their normal position shown in Fig. 6. The locking lever 25 90 may be swung by means of fulcrum shaft 93 carrying it, and this may be the same fulcrum shaft to which the bell crank lever 70 is secured, so that, when the stop motion is brought into action by the movement of 30 the disk or cam 72 to the right the swinging of the lever 70 and the fulcrum shaft 93 causes the pin 91 to be withdrawn, so as to unlock the needle stroke modifying device. When the treadle is depressed for re- 35 starting, the locking pin is again swung into engagement with the hole in the arm 57.

In one aspect it will be seen that this invention comprises a means operative during the stitch cycle for shortening or otherwise rendering abnormal the needle stroke, whether or not used as specifically illustrated for the purpose of missing a thread loop at the time of stoppage so as to leave the work free for removal. The pedal may be con- 40 sidered a controller for putting into effect the timing device or cam, and also the stop- 45 ping device. The cam moving in time with the stitching shaft co-ordinates the needle stroke modifying device with the motions of the other stitching parts. Specifically, my 50 preferred way of securing the modification of needle stroke is through one of the links or levers comprised in the needle actuating mechanism, the same having its effective 55 length or shape varied by shifting of fulcrum, bending or otherwise.

It will thus be seen that I have described a sewing machine embodying the principles and attaining the objects and advantages of 60 the present invention, and other advantages will be apparent to those skilled in the art. Since many matters of combination, ar- 65 rangement, design, detail and other features may be indefinitely varied without depart- ing from the underlying principles, I do not

intend to limit the invention to such features except in so far as specified in the appended claims.

What is claimed is:

1. In a chain stitch sewing machine, a stitching shaft, a barbed needle, connections from the shaft for reciprocating the needle through a normal stroke, means to form a thread loop on the barb of the advanced needle in each normal stroke, and means for changing the needle connections to give the needle an abnormal stroke comprising a toggle device arranged to shift the fulcrum of one of the members of such connections, adapted to cause the needle to advance from normal retracted position to a non-loop-taking position and thereupon to retract without a loop.

2. In a chain stitch sewing machine, a stitching shaft, a barbed needle, crank, link 85 and lever connections from the shaft for reciprocating the needle through a normal stroke, means to form a thread loop on the barb of the advanced needle in each normal stroke, a stop motion adapted to stop the machine with the needle in retracted position, and means operative in the last stitch cycle comprising a toggle arranged to shift the fulcrum of one of such levers so as to change the needle connections whereby the 95 needle will not advance to loop receiving position, and so that the connections become restored to normal during the succeeding needle retraction.

3. In a chain stitch sewing machine, a stitching shaft, a barbed needle, connections from the shaft for reciprocating the needle through a normal stroke, means to form a thread loop on the barb of the advanced needle in each normal stroke, one of the mem- 105 bers of the needle connections being changeable in shape to give the needle an abnormal stroke, to avoid taking the thread loop.

4. In a chain stitch sewing machine, a stitching shaft, a barbed needle, connections 110 from the shaft for reciprocating the needle through a normal stroke, means to form a thread loop on the barb of the advanced needle in each normal stroke, one of the members of the needle connections being a com- 115 pound lever, normally rigid, but adapted to have one part shifted with respect to another to give the needle an abnormal stroke, to avoid taking the thread loop.

5. In a chain stitch sewing machine, a stitching shaft, a barbed needle, means to form a thread loop on the barb of the advanced needle in each normal stroke and actuating the loop forming means in harmony with the needle, one of the levers of such connections being in two parts, normally rigid, but capable of being relatively swung to change the lever shape, whereby to give 125 130

an abnormal actuation to avoid the formation of a loop upon the needle.

6. Machine as in claim 5 and wherein the outer lever part is pivoted to the fulcrumed part and is provided with an extension toward the lever fulcrum, and means adjacent the fulcrum acting on such extension to effect such change of lever shape.

7. Machine as in claim 5 and wherein the outer lever part is pivoted to the fulcrumed

part and is provided with an extension toward the lever fulcrum, and means adjacent the fulcrum acting on such extension to effect such change of lever shape, consisting of a toggle device which normally is straight and holds the lever parts rigidly locked in normal relation. 15

In testimony whereof, I have affixed my signature hereto.

AUGUST R. SCHOENKY.
